DESIGN FOR AN ELECTRIC SHAVING DEVICE

John A. Hanley, Noroton, Conn.

Application November 23, 1937, Serial No. 73,116

Term of patent 14 years

To all whom it may concern:

Be it known that I, John A. Hanley, a citizen of the United States and residing at Noroton, in the county of Fairfield and State of Connecticut, have invented a new, original, and ornamental Design for an Electric Shaving Device, of which the following is a specification, reference being had to the accompanying drawing, forming part hereof, and in which

Fig. 1 is a plan view of the electric shaving device, showing my new design.

Fig. 2 is a side elevation thereof.

Fig. 3 is a rear end view, and

Fig. 4 is a front end view thereof,

The side of my new design opposite that shown in Fig. 1 has the same ornamentation and appearance as the side shown.

I claim:

The ornamental design for an electric shaving device, substantially as shown and described.

JOHN A. HANLEY.
